WELL PIPE ELEVATOR

Chester A. Lundeen, Los Angeles, Calif., and Robert T. Todd, Houston, Tex., assignors to Byron Jackson Co., Vernon, Calif., a corporation of Delaware

Application December 2, 1946, Serial No. 713,476

15 Claims. (Cl. 24—263)

1

This invention relates to well pipe elevators, and particularly to elevators for supporting and handling well casing and tubing of the type having joints formed integrally with the pipe and of only slightly greater diameter than the pipe. The tapered upset joining the joint to the pipe is necessarily of short length and forms only a slight angle, on the order of 5 to 8 degrees, with the pipe axis. Such an upset is insufficient to serve as a shoulder for supporting the pipe.

It is customary to handle long and heavy strings of well casing and tubing by elevators having toothed slips which engage the pipe a short distance below the coupling. Elevators of this type either require manual setting of the slips or are provided with means engageable with the square shoulder of a conventional coupling for automatically setting the slips a short distance below the coupling. Manual setting of the slips is inconvenient inasmuch as when the slips are to be set the elevator is suspended up in the well derrick approximately the full length of a section of casing. Slip setting means adapted for engagement with the square shoulder of a conventional coupling are not suitable for the instant purpose.

A general object of this invention is to provide a well pipe elevator of the slip type incorporating means engageable with a steep upset adjacent the joint for setting the slips.

A further object is to provide slip setting means which, upon engagement with the upset, will yield sufficiently to avoid suspending the pipe by the upset. Preferably the force required to cause the slip setting means to yield is only slightly greater than that required to move the slips downwardly, against the action of their supporting springs, into pipe gripping position.

A further object is to provide slip setting means which is reliable and durable, and which does not unduly increase the size of the elevator.

Other objects will be apparent from the following detailed description of a preferred embodiment and several modifications.

In the drawings:

Figure 1 is a top plan view of an elevator embodying a preferred form of slip setting means with a portion cut away substantially on the line I—I of Figure 3;

Figure 2 is a front elevation of the elevator;

Figure 3 is a vertical sectional view on the line III—III of Figure 1, showing a slip in retracted position;

Figure 3a is a view similar to Figure 3 but show-

2

ing the slip in gripping engagement with the pipe;

Figure 4 is a top plan view of an elevator embodying a modification of the slip setting means;

Figure 5 is a vertical sectional view on the line V—V of Figure 4;

Figure 5a is a view similar to Figure 5, but showing the slip in set position; and

Figures 6 and 7 are sectional views corresponding to Figure 5 and showing other modifications of the slip setting means.

Referring to Figures 1 to 3a, a preferred form of elevator comprises a pair of semicircular body sections 1 and 2 hingedly connected at their rear sides at 3 and having latch means, generally designated 4, for releasably latching the sections together about a pipe. The construction of the body sections and latch are in all essential respects similar to that disclosed in C. A. Lundeen

Patent No. 2,257,120, dated September 30, 1941, to which reference may be had for a more detailed description of the latch. The elevator of the aforementioned patent is adapted for use

with pipe having joints of considerably greater diameter than the pipe and having a tapered upset extending at an angle of about 18° with the pipe axis. This upset is sufficient to serve as a supporting shoulder, and the central opening in the elevator is accordingly provided with a tapered seat to receive the upset.

In the instant case the pipe cannot be supported by the upset because of its slight angularity with the pipe axis. Instead, each body section of the elevator is recessed to provide a

35 downwardly tapered bowl 6. Slips 7, 8, 9 and 10 are mounted within the recess for movement between a raised, inactive position shown in Figure 3 and a lower, pipe-gripping position shown in Figure 3a. Each slip is retained in sliding engagement with the tapered bowl 6 by a retaining bolt 11, the inner end of which is secured by

welding or otherwise in a socket in the slip, the outer end extending through a vertically elongated slot 12 in the elevator body. A nut 13 on the outer end of the bolt overlies a boss on the body surrounding the slot to retain the slip in position (see Figure 2). The inner face of each slip may be provided with pipe gripping means of any desired form. In the present instance three

40 toothed or knurled inserts 14 are mounted in vertical dovetailed slots in the face of the slip, and are retained by a transverse key 15 overlying the upper ends of the inserts and retained in a transverse dovetailed groove in the slip. Each slip is 45 normally held in its raised, inactive position by

a compression spring 16 mounted within a recess 17 in the body outwardly of the bowl 6 and interposed between the base of the recess and the bolt 11. The spring exerts an upward force on the slip only slightly greater than the weight of the slip, so that slight downward pressure will move the slip downwardly and inwardly into gripping engagement with the pipe.

The type of pipe for which this elevator is especially adapted is shown in Figures 3 and 3^a, the steeply tapered upset between the pipe and the joint 20 being shown at 21. In order to set the slips automatically so that they grip the pipe just below the upset as the elevator is raised after being latched about the pipe, means are provided above the gripping portion of each slip for engagement with the tapered upset to arrest further upward movement of the slips as the elevator continues to move upwardly. It is essential that the settling means be yieldable upon application of a predetermined relatively small downward force in order that no appreciable portion of the weight of the string of pipe be supported by the upset. Several alternative yieldable setting means are shown in Figures 3, 5, 6 and 7.

Referring to Figures 3 and 3^a, a block or strip 22 of resilient material such as neoprene or the like is mounted in a transverse dovetailed groove 23 in each slip. As shown most clearly in Figure 1, the groove 23 extends the full width of the slip to permit insertion of the strip 22 thereinto from one side. The strips may conveniently be cut from a straight strip of the desired trapezoidal cross section, and, when flexed from their normally straight form to conform to the curvature of the groove 23, the tendency to straighten out will exert sufficient frictional engagement with the walls of the groove to retain them in place without other retaining means.

It will be noted that the inner face of the slip above the inserts 14 is tapered to conform to the taper of the upset 21 on the pipe, and that the inner face of the resilient strip 22 is similarly tapered in order to afford full surface contact of the strip with the upset. From a comparison of Figures 3 and 3^a it will be apparent that upon arresting the upward movement of the slips by engagement of the strips 22 with the upset 21, the slips are forced inwardly by continued upward movement of the elevator body. In order to permit this inward movement of the slips, the resilient strip is deformed approximately as shown in Figure 3^a. A relief groove 24 is provided at the outer side of the strip to permit the strip to bulge outwardly. If preferred, the strip 22 could be provided with one or more internal recesses or pockets to permit the desired amount of displacement of the inner face.

The elevator body is provided with upper and lower inwardly extending ribs 25 and 26. The upper rib 25 is bored to a diameter only slightly larger than that of the pipe joint 20, and the lower rib 26 is bored to a slightly greater diameter than that of the pipe. Inasmuch as the upper rib 25 is opposite the joint 20 when the resilient strip 22 contacts the upset, the two ribs adequately center the elevator on the pipe prior to setting of the slips. It will be noted with reference to Figure 3 that the inner faces of both the inserts 14 and the strips 22 are disposed radially outwardly of the inner periphery of the lower rib 26 when the slips are in their raised position, and hence there is no possibility of either the inserts 14 or the strips 22 dragging

on the pipe and causing premature setting of the slips. An adjusting screw 27 is threaded through the upper rib 25 to adjustably limit the upward movement of the slips under the influence of the springs 16 when the elevator is removed from the pipe.

In order to adapt the same elevator body to use with interchangeable slips which fit smaller sizes of pipe, a groove 28 is formed in each lower rib 26 to receive guide plates which extend inwardly into close proximity to the smaller pipe. Similar guide plates may also be mounted on the upper surface of the upper rib 25 and held in place by the lock nuts 29 for the adjusting screws 27.

Referring now to Figures 4 and 5, the elevator body is in all essential respects similar to that of Figures 1 and 2 and comprises pivotally connected sections 29 and 30. The slips and the slip setting means are, however, different in form but embody the same principle of automatic setting. In this instance each slip 31 (Figure 5) is provided with a central longitudinal slot 32 to accommodate a guide pin 33 rigidly mounted in the elevator body. A compression spring 34 surrounds the guide pin and bears against the lower face of the slip to urge it upwardly into inactive position. The elevator body sections 29 and 30 are provided with a downwardly tapered surface 35 with which a similarly tapered surface 36 on each slip has wedging engagement when the slips are set. Above the tapered surface 35 the recess in the body is tapered upwardly at 37, for a purpose which will be presently described.

In this embodiment of the invention the slip setting means is in the form of an auxiliary slip 38 mounted within a recess in the upper portion of each slip 31 and vertically slotted at 39 to accommodate the guide pin 33. The inner face of the auxiliary slip is tapered downwardly to conform to the taper of the upset 21 on the pipe, and as shown it is provided with serrations to aid in gripping the upset. The bottom wall 40 of the recess in the slip is inclined downwardly and inwardly at an angle of about 45°, and is engaged by a similarly inclined lower surface 41 on the auxiliary slip. A relatively stiff compression spring 42 is interposed between a shoulder 43 on the auxiliary slip and the upper wall 44 of the recess in the slip. The spring 42 thus urges the auxiliary slip downwardly and radially inwardly relative to the main slip 31.

As in the previously described form of the invention, the spring 34 exerts an upward force only slightly greater than the weight of the slip. The spring 42, on the other hand, is sufficiently stiff to resist the pressure normally required to set the slips. Its function is to permit the auxiliary slip to move upwardly and outwardly relative to the main slip as the latter moves into gripping position, and to limit to a small amount that portion of the weight of the string of pipe which can be transmitted to the elevator through the upset 21. It will be noted that only a slight clearance at 46 is provided between the outer surface of the auxiliary slip and the upwardly and inwardly tapered surface 37 on the body. This provides a safeguard against the possibility of the auxiliary slip moving upwardly and outwardly a sufficient distance to permit it to clear the upset 21 and allow the tool joint 20 to pass through the elevator in the event the main slips should become stuck in their raised position.

The mode of operation of this form of the invention will be apparent from a comparison of

Figures 5 and 5^a. As the elevator is raised along the pipe and the auxiliary slips 38 engage the pipe upset 21, further upward movement of the main slips is stopped. Upon continued upward movement of the elevator body, the springs 34 are compressed and the tapered wedge surfaces 35 and 39 force the slips 31 inwardly into gripping engagement with the pipe. Inward movement of the auxiliary slips is restrained by their engagement with the upset 21, and they are therefore constrained to move upwardly and outwardly relative to the main slips along the inclined surfaces 40, into the position indicated in Figure 5^a.

In the form of the invention shown in Figure 6, auxiliary slips 50 having inner, serrated surfaces tapered to conform to the taper of the pipe upset are employed, as in Figure 5. In this instance each auxiliary slip is mounted within a recess in a housing 51 separate from the main slip 52 and being supported thereabove by lugs 53 engaging the upper surface of the slip. The housing 51 is mounted for vertical sliding movement in the elevator body and is provided with a downwardly tapered surface 54 engaged by a similarly tapered outer surface on the auxiliary slip 50. A relatively stiff spring 55 urges the auxiliary slip downwardly in the housing recess, and is yieldable to permit the auxiliary slip to move upwardly and outwardly as the main slip is moved into gripping position.

Figure 7 illustrates another form of slip setting means which in several respects is generally similar to that shown in Figure 2. In this embodiment of the invention a cylindrical bore is formed in the upper portion of each slip 61, with its axis extending normal to the tapered upset 21 on the pipe. A plunger is mounted for limited sliding movement in the bore, its outward movement being limited by a screw 63 threaded into the upper portion of the slip and engaging a groove 64 in the plunger. The plunger is urged toward the pipe by a resilient member 65, herein shown as a hollow cylinder of rubber, neoprene or the like, although it will be obvious that a helical compression spring would serve the same purpose. The resilient member 65 possesses sufficient rigidity to cause engagement of the plunger with the pipe upset 21 to set the slip 61, but will yield to permit the required retraction of the plunger into its bore as the slip moves into gripping engagement with the pipe.

Having fully described our invention, it is to be understood that we do not wish to be limited to the details herein set forth, but our invention is of the full scope of the appended claims.

We claim:

1. A well pipe elevator for use with pipe having a downwardly tapered upset adjacent a joint, comprising: a body having a downwardly tapered bore therein; tapered sectional slips mounted within said bore and yieldably urged to pipe disengaging position; slip setting members movably mounted in said body and arranged, upon movement thereof, to move said slips along said bore into pipe engaging position; said slip setting members having upset-engaging portions; means on said body to hold said portions spaced from said pipe at such distance that they are engageable only with a tapered upset to produce slip setting movement thereof; the said upset-engaging portions of said slip setting members being yieldably movable outwardly relative to said slips in a direction inclined at an oblique angle to the axis of the pipe whereby to limit the portion of the weight of the pipe carried by the upset.

2. A well pipe elevator as set forth in claim 1 wherein said means to hold said portions spaced from said pipe includes a lower flange extending radially inwardly in close proximity to the pipe and said upset-engaging surfaces define a circle of greater diameter than said flange but of lesser diameter than the upset portion of said pipe.

3. A well pipe elevator as set forth in claim 1 wherein the combination includes a spring yieldably resisting movement of said slip-setting members relative to said slips.

4. A well pipe elevator as set forth in claim 1 wherein said slip-setting members slope in conformity to the taper of the upset portion of the pipe, are engageable therewith and thereupon move relative to the slips, and wherein the combination includes a spring yieldingly resisting said relative movement.

5. A well pipe elevator as set forth in claim 1 wherein said slip-setting members are movable relative to said slips in a direction having a vertical component, and wherein the combination includes a spring yieldingly resisting such relative movement.

6. A well pipe elevator as set forth in claim 1 wherein said slip-setting members comprise yieldably urged plungers mounted in the slips for movement in a direction normal to the tapered upset of the pipe.

7. A well pipe elevator as set forth in claim 1 wherein said slip-setting members are bodies of yieldable material set in said slips.

8. A well pipe elevator as set forth in claim 1 wherein said slip-setting members are metallic members having gripping teeth adapted to conform to the upset portion of said pipe and include tapered surfaces adapted for sliding cooperation with said slips and wherein the combination includes a spring urging said slip-setting members against the upset portion of said pipe.

9. A well pipe elevator as set forth in claim 1 wherein the combination includes: housings movable relative to said body and engageable with said slips having tapered inner surfaces, each slip-setting member being carried within a housing and having a tapered surface cooperating with said tapered housing surface, and springs urging said slip-setting members against said tapered housing surfaces.

10. A well pipe elevator for use with pipe having a downwardly tapered upset adjacent a joint, comprising: a body having a downwardly tapered bore, yieldably supported sectional slips mounted within said bore and having tapered surfaces cooperating with said tapered bore; and slip-setting members carried by said slips and having surfaces engageable with the upset on the pipe to slide said slips relative to said body to gripping engagement with the pipe below the upset, means normally holding said surfaces spaced from the pipe, said slip-setting members being yieldable relative to the slips in a direction inclined at an oblique angle to the axis of the pipe whereby to limit the portion of the weight of the pipe which is carried by the upset.

11. A well pipe elevator for use with pipe having a downwardly tapered upset adjacent a joint, comprising: a body having a downwardly tapered bore, yieldably supported sectional slips mounted within said bore and having tapered surfaces cooperating with said tapered bore, each of said slips having a recess in its upper portion; and slip-setting members mounted in said recesses and having surfaces engageable with the upset

on the pipe to slide said slips relative to said body to gripping engagement with the pipe below the upset, means normally holding said surfaces spaced from the pipe, said slip-setting members being yieldable relative to the slips in a direction inclined at an oblique angle to the axis of the pipe whereby to limit the portion of the weight of the pipe which is carried by the upset.

12. A well pipe elevator for use with pipe having a downwardly tapered upset adjacent a joint, comprising: a body having a downwardly tapered bore, yieldably supported sectional slips mounted within said bore and having tapered surfaces cooperating with said tapered bore, each of said slips having an arcuate groove above its pipe-gripping portion; and slip-setting members each comprising a body of resilient material fitted in said grooves and having surfaces engageable with the upset on the pipe to slide said slips relative to said body to gripping engagement with the pipe below the upset, means normally holding said surfaces spaced from the pipe, the said surfaces of said slip-setting members being yieldable relative to the slips in a direction inclined at an oblique angle to the axis of the pipe whereby to limit the portion of the weight of the pipe which is carried by the upset.

13. A well pipe elevator for use with pipe having a downwardly tapered upset adjacent a joint, comprising: a body having a downwardly tapered bore, yieldably supported sectional slips mounted within said bore and having tapered surfaces cooperating with said tapered bore, each of said slips having an arcuate groove above its pipe-gripping portion; and slip-setting members each comprising a normally straight strip of resilient material bent into conformity with said grooves and held therein by frictional engagement with the walls thereof and having surfaces engageable with the upset on the pipe to slide said slips relative to said body to gripping engagement with the pipe below the upset, means normally holding said surfaces spaced from the pipe, the said surfaces of said slip-setting members being yieldable relative to the slips in a direction inclined at an oblique angle to the axis of the pipe whereby to limit the portion of the weight of the pipe which is carried by the upset.

14. A well pipe elevator for use with pipe having a downwardly tapered upset adjacent a joint, comprising: a body having a downwardly tapered bore therein; tapered sectional slips mounted within said bore and yieldably urged to pipe disengaging position; slip setting members movably

5 mounted in said body and arranged, upon movement thereof, to move said slips along said bore into pipe engaging position; said slip setting members having upset-engaging portions; means on said body to hold said portions spaced from said pipe at such distance that they are engageable only with a tapered upset to produce slip setting movement thereof; the said upset-engaging portions of said slip setting members being yieldably movable outwardly and downwardly relative to said slips whereby to limit the portion of the weight of the pipe carried by the upset.

15. A well pipe elevator for use with pipe having a downwardly tapered upset adjacent a joint, comprising: a body having a downwardly tapered bore therein; tapered sectional slips mounted within said bore and yieldably urged to pipe disengaging position; slip setting members movably mounted in said body and arranged, upon movement thereof, to move said slips along said bore into pipe engaging position; said slip setting members having upset-engaging portions; means on said body to hold said portions spaced from said pipe at such distance that they are engageable only with a tapered upset to produce slip setting movement thereof; the said upset-engaging portions of said slip setting members being yieldably movable relative to said slips in a direction substantially normal to the surface of said tapered upset whereby to limit the portion of the weight of the pipe carried by the upset.
